(57) **CLAIM**

The ornamental design for a kayak anchor bracket, as shown and described.

DESCRIPTION

FIG. 1 is a perspective view of a kayak anchor bracket; FIG. 2 is a front view thereof; FIG. 3 is a back view thereof; FIG. 4 is a right side view thereof; FIG. 5 is a left side view thereof; FIG. 6 is a top view thereof; FIG. 7 is a bottom view thereof; and, FIG. 8 is a perspective view thereof as positioned on a kayak.

The broken lines showing a kayak illustrate environment and form no part of the claimed design. Further, the broken lines showing portions of the article form no part of the claimed design.
